SKIN BUFFER

Robert H. Griffin, Yonkers, N. Y.

Application March 30, 1950, Serial No. 152,782

21 Claims. (Cl. 51—72)

1

This invention relates generally to buffing devices and more particularly to buffers for buffing skins, hides and the like.

The primary object of the invention is to provide an improved buffer for buffing skins and like work, whereby the work is buffed uniformly.

Another object of the invention is to provide an improved buffer, wherein the buffing medium acts on a smooth, taut work surface.

An additional object of the invention is to provide an improved buffer of the multi-pass type, whereby skins can be buffed uniformly by a relatively unskilled operator.

A further object of the invention is to provide an improved buffer of the multi-pass type, capable of buffing skins of different thicknesses without reseating.

Another object of the invention is to provide an improved buffing roll for a buffer, utilizing centrifugal force to apply buffing pressure to the abradant, whereby the abradant is enabled to accommodate itself to any surface irregularities in the work.

An additional object of the invention is to provide an improved buffing roll for a buffer, formed of one or more uniform sections, whereby the roll may readily be adjusted to accommodate work of different widths.

An additional object of the invention is to provide a buffing roll for a buffer, having a plurality of abrasive sleeves so arranged and secured peripherally of the roll as to provide a uniform buffing action over the entire width of the work.

Another object of the invention is to provide in a buffer, a work-presenting device by which work is subjected both to longitudinal and transverse spreading forces, ensuring its presentation to the buffing medium in smooth, unwrinkled condition.

A further object of the invention is to provide in a buffer, a work-presenting device by which drawing of a skin by the operator past the abrading medium is yieldably resisted by a substantially constant force which is independent of the buffing pressure.

Other objects and advantages of the invention will appear hereinafter in the detailed description, be particularly pointed out in the appended claims, and illustrated in the accompanying drawings in which:

Figure 1 is a vertical sectional view of the improved buffer of the present invention, taken along the lines 1—1 of Figure 2;

Figure 2 is a front elevational view of the buffer of Figure 1;

2

Figure 3 is a vertical sectional view, taken along the lines 3—3 of Figure 2;

Figure 4 is a side elevational view on an enlarged scale of the buffing roll of Figure 1;

Figure 5 is an isometric view on an enlarged scale of the nose-piece of the skin-presenting mechanism;

Figure 6 is an isometric view of the angle-iron on which the back board of the skin-presenting mechanism is mounted;

Figure 7 is a fragmentary view on an enlarged scale of the upper end portion of the back-up board of Figure 3, showing the details of construction of its setting-out unit;

Figure 8 is a transverse sectional view on an enlarged scale, taken along the lines 8—8 of Figure 7;

Figure 9 is a front elevational view of the buffing roll of Figure 4;

Figure 10 is a side elevational view of one of the sections of the drum of Figure 4;

Figure 11 is a front elevational view of the section of Figure 10, with portions broken away to more clearly illustrate certain of the details of construction; and

Figure 12 is a fragmentary isometric view of an abrasive core and its associated anchor bar.

While the buffer of the present invention is of broad usage, the illustrated embodiment is particularly designed for use on skins, hides and the like, hereinafter termed "skins." In such use, the buffer may be employed for buffing both the grain and flesh sides of skins, these operations in a tannery being termed, respectively, "snuffing" and "buffing," but here being grouped under the more general term "buffing." The illustrated buffer is of the multi-pass type in which the buffing mechanism is mounted on a suitable frame of the same general type as those employed for conventional multi-pass machines. As with the conventional machine, a skin is placed or laid by the operator on the back-up or skin-presenting portion of the mechanism, the operator maintaining a grip on the upper or outer edge of the skin. With the skin in place, the presenting portion of the mechanism is actuated to bring the surface of the skin into contact with the buffing roll of the mechanism, and the skin is then gradually withdrawn by the operator, progressively to treat its surface from the point of initial contact to its outer end, the pressure exerted on the skin and the speed at which it is withdrawn being entirely controlled by the operator. After the skin has been withdrawn, it is reversed and its opposite end treated in the same manner.

The device of the present invention is designed to buff the skin uniformly, and without possibility of burning or scorching, by setting-out the skin as it is drawn into contact with the buffing roll to present a smooth, unwrinkled surface, and buffing the skin with an abrasive medium deriving its buffing pressure from centrifugal force.

In treating skins, whether in automatic machines or in the multi-pass type of machine, just described, it is desirable that a skin be presented for buffing in smooth, taut condition and, particularly on the grain side, that the abrading medium be able to accommodate itself to the variations in grain, and on both sides that the pressure exerted on the skin be held to a minimum to prevent scorching of the skin. The buffing roll of the illustrated buffing device is particularly designed to produce such action.

Referring now in detail to the drawings in which like reference characters designate like parts, the improved buffer of the present invention is provided with a frame 1 having a base 2 and transversely spaced uprights or supports 3, on the latter of which are journaled the ends of a shaft or axle 4 of a rotary buffing roll, drum, member or device 5. The buffing roll may be driven directly or, as illustrated, by a variable speed drive through a pulley 6 affixed to the roll shaft 4 and drivably connected to a drive shaft 7 having a multi-stage, power take-off pulley 8.

Associated with the buffing roll, and disposed substantially parallel to the axis of the shaft 4 thereof, is a back-up or skin-presenting device, member or mechanism 9 by which a skin is presented for buffing by the buffing roll. The back-up member, preferably of somewhat greater width or extent than the buffing roll, is also mounted on the uprights 3 of the frame 1 outwardly of the roll. It is comprised of two main parts, one a back board or inner jaw 10 and the other, a back-up board or outer jaw 11. Of the two boards, the back board 10 is substantially vertically disposed with its inner face or surface 12 positioned somewhat below the axis and beyond the periphery of the buffing roll, longitudinally of the frame. The back-up board is mounted on the frame 1 and, for reasons to be hereinafter pointed out, at least its upper portion is adapted to move yieldably toward the buffing roll. This may be accomplished by hinging the lower end of the back board and yieldably mounting its upper end, or, as shown, by yieldably mounting the back board in its entirety by attaching to the inner face 13 of each of the uprights 3 a substantially vertically disposed angle-iron 14, having one leg 15 in abutment or engagement with the associated upright and the other leg 16 disposed or projecting inwardly thereof, transversely of the frame. The back board is connected to each of these inner, transverse legs 16 by vertically spaced bolts 17, the stems or shanks 18 of which are encircled by coil springs 19 acting between the back board and the angle-irons 14 and normally urging the back board away from the buffing roll, the limit of such movement being adjustable through nuts 20 threadedly engaging the inner ends of the bolts. Adjustment of the angle-irons relative to the frame is also contemplated by the provision of vertical slots 21 in the frame-engaging legs 15 of the angle-irons and intersecting horizontally disposed slots 22 in the frame, in which ride connecting bolts 23, the slots enabling the angle-irons and, with them, the back board to be shifted in any direction parallel to the uprights 3.

Confronting or opposing the outer face 12 of the back board and, in operative position, disposed substantially parallel thereto is the back-up board or outer jaw 11. This board is intended 5 to serve as the movable, shiftable, pivoted or hinged jaw or element of the back-up member and, for this purpose, is pivotally or hingedly attached, adjacent its lower end, to the uprights 3 by a bar, rod or other shaft 24 having its ends 10 carried by the uprights and its intermediate portion encircled by transversely spaced collars 25 attached to the outer face 26 of the back-up board 11, which may be formed as part of hinges or hangers 27 having downwardly extending 15 lower arms or levers 28 through which the back-up board may be pivoted or oscillated. For actuating the back-up board, through the levers 28, the latter are connected by adjustable links 29 to the upper legs 30 of a pair of bell cranks 31, on the lower legs 32 of which is carried an actuating treadle or step 33. The upper portion of 20 the back-up board is normally held away from the back board 10 by a coil spring or like resilient means 34 which, conveniently, may extend between a cross-member 35 of the frame and a cross-bar 36 connecting the lower arms 28 of the hinges 27. The extent of movement of the treadle 33, and thus, the opening between the jaws on movement of the back-up board 11 against the force of the spring 34, may be limited 25 by a stop or abutment 37 on the frame, against which the treadle is adapted to abut, the extent to which the back-up board is swung within this limit being adjustable by adjustment of the links 29.

Attached or secured to and extending across the upper end of the back-up board is a back-up element, nose-piece or tongue 38 which projects inwardly from its inner or back board-confronting face 39 and, when the boards are in operative or closed position as shown in Figure 1, is adapted to overlie the upper end of the back board 10. This nose-piece is substantially a right-triangle in cross-section, with its under 40 face 40 tapering or inclined upwardly away from the back-up board, the nose-piece terminating in a rounded, relatively narrow or thin, outer end or nose 41. As shown, the nose extends across the buffing roll 5 and is adapted to be moved substantially to the periphery of the roll to present a surface of a skin for buffing when the treadle 33 is depressed. This nose may be made of wood, a material suitable for the boards and the balance of the nose-piece, but is preferably 45 of metal because of its greater wear resistance.

To ensure that buffing will be limited to that portion of a skin backed-up by the rounded nose 41 and that contact will then be obtained across the entire width of the skin, the nose is preferably struck about an axis substantially parallel 50 to and in the same horizontal plane as the axis of the axle 4 of the buffing roll. Such engagement of a skin with the buffer at the maximum horizontal distance from the axis of the latter 55 also permits ready observation by the operator of the extent of buffing. Additionally, the nose is positioned at a height above ground consistent with most efficient handling of a skin, the upper surface 42 of the nose-piece being substantially horizontally disposed for the same purpose.

The aforementioned yieldable mounting of the back board 10 is employed to provide a substantially constant resistance to pull or withdrawal of a skin by the operator, independently of both 60 the extent or amount of the buffing pressure and,

over a wide range, the thickness of the skin. This is obtained by attaching to the inner face 43 of the back board, adjacent its upper end, an inwardly projecting lip or ledge 44 having a downwardly inclined upper face 45 which underlies or underrides and is substantially parallel to a substantial portion of the inclined under or lower face 40 of the nose-piece 38, when the back-up board 11 is in operative or closed position. These confronting surfaces provide, therebetween, a guide channel 46 having a gripping element or surface on either side by which a skin is yieldably or resiliently gripped, by virtue of the resilient mounting of the back board, as the skin is fed to or drawn into engagement with the buffing roll. By yieldably mounting both the upper and lower end portions of the back board, in the manner illustrated, the board is caused to be displaced substantially horizontally, the extent depending upon the thickness of the particular skin being buffed, thus maintaining the parallel disposition or alignment of the confronting or gripping faces, 40 and 45.

Below the lower level of the lip 44, there are mounted on the confronting faces of the boards, these their outer and inner faces 12 and 39, respectively, a setting-out device in the form of opposed, coacting rolls 41, a plurality of which are mounted on each board. Each of the rolls is formed of a plurality of ball or like bearings 48 mounted on a common shaft 49, having its ends carried by spaced ears or lugs 50, separated from the associated board by a bearing plate 51 on which the setting-out unit of each board is mounted. These units may be attached to their associated board by bolts 52 extending through the board and bearing plate and threadedly engaging the lugs 50. The several rolls of the setting-out unit of each board are divided by the longitudinal center line of the board into a pair of divergent or angularly disposed groups of rolls, the rolls of each group being inclined downwardly toward the outer edge of the board and arranged in oblique or echelon formation, with the contiguous bearings of adjacent rolls preferably overlapping longitudinally of the board. With corresponding rolls on each board confronting when the boards are in closed or operative position, a skin will be spread or set-out transversely as it is drawn upwardly by the rolls. These rolls are adapted to accommodate skins of different thickness by yielding of the back board in the manner previously described. With the setting-out rolls spreading a skin transversely or laterally, and the gripping surfaces of the nose-piece 38 and lip 44 opposing longitudinal movement, an operator, merely by withdrawing or pulling out a skin when the boards or jaws, 10 and 11, are closed by actuation of the treadle 33, causes a skin to be spread both longitudinally and transversely before it reaches the back-up nose 41, and thus ensures that a skin, when brought into line contact with the buffing roll, will present thereto a smooth, unwrinkled surface.

Presented in smooth, taut condition by the back-up member 9, a skin is enabled to be buffed uniformly and without danger of scorching or being cut through by the form of buffing roll here employed. Mounted on the frame 1, in the manner previously described, the buffing roll 5 is comprised of a drum, cylinder or support 53 mounted on the shaft 4. To enable its width to be varied to adapt it readily to handle work of any width, depending upon the effective width of the back-up member 9 with which it is employed, the drum

may be formed of a plurality of uniform or standard sections or segments 54. To reduce its weight, each of the sections preferably has a hub 55 and a radially spaced, annular rim or flange 56, connected by a plurality of spokes or arms 57 projecting radially from the hub. For drivably connecting the several sections, the shaft 4 may be longitudinally slotted to receive a common key 58 engaging a like keyway in each of the several hubs 55, the hubs additionally being provided with individual set screws 59 for fixing their positions axially of the shaft.

It is the usual practice in buffing rolls to employ a single abrasive sleeve, wrapped around the roll, as the abrading medium. In the roll of the present invention there are employed, instead, a plurality of abrasive loops positioned about the periphery of the roll in staggered relation, and so anchored or attached thereto as to limit the pressure applied to the work being buffed to the centrifugal force exerted on the abrasive loops by rotation of the roll. To this end, the outer wall or surface of the rim 56 of each drum section or unit 54 is interrupted by a plurality of radially arranged, axially extending grooves, seats or channels 60, spaced circumferentially by axially extending ribs or splines 61, forming the intervening portions of the rim. To accommodate the particular form of anchoring means employed in the illustrated embodiment, the grooves 60 are concavely arcuate or substantially semi-cylindrical, thus, with the intervening ribs, imparting to each section the appearance of a sprocket wheel. When assembled into a roll of the desired width, the grooves of the several sections are intended to align into continuous grooves extending the full length of the roll, such alignment being obtainable through the key 58 and its associated keyways. When assembled, it is desirable that both the rims 56 and hubs 55 of adjoining or contiguous sections abut, to minimize stresses. The several sections may then be held together or connected by suitable means, such as the illustrated axially disposed bolts 62 projecting through aligned openings 63 in the spokes 57 of the several sections.

Looping of the abrasive medium about the periphery of the drum 53 is accomplished by the provision of a plurality of cores, collars or frame members 64, each adapted to be inserted in and encircled by an abrasive sleeve or tube 65. These cores are tubular, being formed as rings, hoops or bands, and are made of resilient or flexible material. The cores are of such shape that they conform to the contour of the grooves 60, when fixed or seated therein, and thus clamp, grip, fasten or anchor the associated abrasive sleeves 65 against the confronting walls of the grooves.

For retaining or securing the cores 64 and their associated abrasive sleeves 65 in the grooves 60, there may be provided lock, retaining, fastening or anchor bars or members 66. These bars are insertable through the cores and removably secured to the rim 56 by anchor bolts 67 threadedly engaging holes 68 at the bottoms of the grooves. A single bar is employed for each of the grooves, the bar extending the length of its groove and securing therein one or more of the cores, depending on the length of the roll. The bars, preferably, are rectangular in section and made of aluminum or like material, this metal taking a sufficient bend or deformation on tightening of the anchor bolts 67 to prevent the cores from shifting axially of the roll.

Were each of the cores 64 of circular section,

it would effectively clamp the associated sleeve 65 in its groove or seat 60, but would also provide a relatively stiff backing for the outer portion of the sleeve causing the abradent to cut or gouge any portion of the presented skin of greater thickness than that for which the buffer was set. Accordingly, while the main or lower portions 69 of the cores are cylindrical in contour and conform to the conformation of the seats 60 in the drum 53, their outer portions or faces 70 are spaced inwardly of the corresponding abrasive sleeves 65, enabling the sleeves to project therebeyond in the form of unsupported or unbacked loops 71. Such sleeves have been found to buff with optimum efficiency if their normal cylindrical contour or shape is retained on rotation of the buffing roll. However, if the portion of the sleeve beyond the periphery of the drum 53 is entirely unsupported, it has been found that the sleeve will distort progressively out of its normal shape as the speed of the roll is increased. Accordingly, the cylindrical or sleeve-engaging portions 69 of the cores project somewhat beyond the periphery of the drum to enable their projecting end portions to serve as guide elements for controlling or maintaining the conformation or shape of the sleeves, regardless of the speed of the roll.

If the cores 64 ended in unconnected edges, they would both tend to cut the associated sleeve and gouge a skin if accidentally brought into engagement with the skin. Additionally, it has been found that the projecting end portions of the cores, if unconnected, have almost as great a tendency to deform, on rotation of the buffing roll, as do the sleeves. Accordingly, the aforementioned outer portions of the sleeves are utilized both to protect the upper ends of the cylindrical portions 69 against deformation and, by merging with the cylindrical portions in rounded, outer shoulders 72, to minimize possible damage to a skin. In the illustrated embodiment, these requisites are obtained by flattening the outer face or portion 70 of each core through the provision of substantially flat reentrant wings 73 obtained by inturning the edges of the core on either side, the wings overlapping at the center and there being joined by suitable means, such as the disclosed rivets 74. While preventing spreading or expansion of the cores on rotation of the roll, the wings, also being resilient or flexible, are enabled to bow or bend outwardly or inwardly, thus rendering the cores contractible or compressible. Although this inward bendability of the wings, coupled with the rounding of the outer shoulders 72, would minimize damage should either accidentally bear against a skin, it is preferred that the wings and shoulders be spaced sufficiently inwardly of the normal outer extremities or outermost end portions of the loops 71 to permit the latter to yield within limits including any possible variations in thickness of the group of skins being buffed.

To maintain the cores 64 with their openings outwardly facing, there is formed in each, beyond the reentrant wings 73, a pair of reverse-curved or outturned legs or positioning members 75 which are disposed below or radially inwardly of the shoulders 72, and are adapted at their outward ends to engage or rest on the outer surfaces of the adjacent or bounding ribs 61. These legs also serve as an abutment to position the abrasive sleeves 65 on the core, by limiting the extent to which the core is insertible in the sleeve. Consequently, by making the abrasive

sleeves of the same length as the reentrant wings 73 of the cores, uniform clamping and support of the sleeves throughout their lengths is assured.

As shown, the cores 64 and the abrasive sleeves 65, supported thereby, are disposed about the periphery of the assembled sections 54 in staggered relation. In the illustrated embodiment, this is obtained by seating three cores in each of the grooves 60, these alternating in their spacing, axially of the roll, with the cores in the adjoining grooves and facing in the opposite direction. There are thus provided six circumferential sets or bands of loops which are overlapped slightly to ensure that the surface of the work will be buffed over its entire width. So mounted, the legs of each core will serve to limit axial shifting of the adjacent cores of adjoining grooves in one direction, should the hold-down or anchor bar of one axial row of cores accidentally become loosened. Shifting of the cores in the opposite axial direction is limited by the heads of the associated anchor bolts. To prevent a core from being thrown off either end of the roll, there are provided, on the opposite ends of the roll, stop means which may be in the form of screws 76 carrying washers 77, each of the latter projecting within the marginal edges of the adjacent grooves and being adapted to engage the confronting end of the endmost core in one of the grooves.

A feature of the buffing roll of the present invention is that it not only presents its abrading medium in loop form and, by reliance on centrifugal force, is enabled to follow any irregularities in contour of the surface being buffed, but that full use can be made of the abrading surface of each of the abrasive sleeves 65. After the roll has operated for a period, the contacting surfaces of the several abrasive loops will, of course, show wear. When this approaches the stage at which further buffing would be less efficient, the roll is stopped. Then, by loosening the several anchor bolts 67 and compressing the cores by pinching in their positioning legs 75, the sleeves may readily be turned about their cores to expose a fresh working surface.

As previously mentioned, the illustrated buffer is of the multi-pass type in which the operator pulls part of a surface of a skin past the buffing roll in one pass and reverses the ends of the skin for a second pass, to buff the remainder of the surface. Current buffing machines of this type generally utilize the pressure exerted on a skin by their buffing and back-up members to resist the pull of the operator and thus obtain substantially uniform buffing of its surface. However, in the instant buffer, the buffing pressure is limited to the centrifugal force on the unbacked loops of the abrasive sleeves 65 and affords insufficient drag to enable an operator effectively to control the buffing. Consequently, the conventional back-up members would not suffice and are here replaced by the multi-jawed back-up member 9 by which the necessary drag is supplied independently of buffing pressure.

In operation of the disclosed buffer, the jaws, 10 and 11, are normally held open by the spring 34 which, by acting on the hinged jaw 11, causes the nose-piece 33 to be withdrawn or displaced sufficiently from its operative position to expose the opening between the jaws. The operator drops or places the outer end portion of a skin within this opening and, by depressing the actuating treadle 33, causes the jaws to close and

the skin to be engaged by the setting-out rolls 47 and the opposed gripping surfaces of the nose-piece and the lip 44. The limit of movement of the nose-piece having been previously set by adjustment of the links 29 to take the range of thickness of the skins to be buffed, actuation of the treadle thereafter enables the buffer, by virtue of the yieldability of the inner jaw 11 and the abrasive loops 11, automatically to accommodate itself to variations in the several skins. At the same time, the pull exerted on the skin by the operator reacts through the setting-out rolls and yieldable grip to spread the skin both longitudinally and transversely, such that the surface presented to the buffing roll is smooth and enabled to be uniformly buffed. The buffing will, of course, produce a considerable amount of dust composed of waste particles of abrasive grit and skin. If desired, this dust can be removed continuously during the operation by partially enclosing the buffing roll in a conventional suction hood (not shown).

From the above detailed description, it will be apparent that there has been provided an improved buffer of wide application and particularly suited for buffing skins, which effectively sets out work, ensuring its presentation for buffing in smooth, taut condition, is enabled automatically to accommodate itself to work of a considerable range of thickness, and is adapted, through the form of its abradant, to buff the work uniformly, regardless of surface irregularities. It should be understood that the described and disclosed embodiment is merely exemplary of the invention and that all modifications are intended to be included which do not depart either from the spirit of the invention or the scope of the appended claims.

Having described my invention, I claim:

1. A buffer comprising a movable support, abrasive loops carried by and projecting outwardly beyond said support, means in and spaced inwardly of the outermost portions of said loops for limiting the minimum projection of said loops and anchoring said loops to said support, a back-up member displaceable relative to said support for presenting work to said loops, and means carried by said back-up member for yieldably resisting passage of said work past said support independently of pressure exerted thereon by said loops and back-up member.

2. A buffer comprising a buffing drum, abradant clamped to and projecting in unbacked loop form peripherally of said drum, a back-up member displaceable relative to said drum for presenting work to said abradant, and means carried by said back-up member for yieldably resisting passage of said work past said abradant independently of pressure exerted thereon by said abradant and back-up member.

3. A buffer comprising a buffing drum, abradant clamped to and projecting in unbacked loop form peripherally of said drum, a back-up member displaceable relative to said drum for presenting work to said abradant, and means carried by said back-up member and operative on withdrawal of work therefrom for spreading work longitudinally and transversely and presenting said work in smooth, taut condition to said abradant.

4. A buffer comprising a buffing drum, abradant clamped to and projecting in unbacked loop form peripherally of said drum, a back-up member for presenting work to said abradant, said member having a pair of jaws movable relative

to each other and to said drum, and means carried by each of said jaws and coacting on closing thereof for exerting longitudinal and transverse spreading forces on work withdrawn from said jaws into buffering engagement with said abradant.

5. A buffer comprising a buffering drum rotatably mounted on a frame, abrading means carried by and projecting in a plurality of unbacked loops beyond the periphery of said drum, a back-up member for presenting work to said drum, said back-up member having a jaw associated with said drum and yieldably mounted on said frame and a second jaw confronting said yieldable jaw and pivotal relative thereto for opening and closing said jaws, means normally maintaining said jaws in open position, means for closing said jaws, and means carried by and operative on closing of said jaws for setting-out 15 a skin withdrawn from said jaws into engagement with said abrading loops.

6. In a buffer having a movable buffering device, the combination of a back-up member shiftable relative to said buffering member for presenting work thereto, a yieldably mounted member confronting said back-up member, means carried by said members and positioned in advance of a work-presenting surface of said back-up member for yieldably resisting movement of said work past said buffering member independently of buffering pressure exerted thereon, and means carried by said members and associated with said resisting means for spreading said work prior to presentation thereof to said buffering member.

35 7. A buffer comprising a rotary drum, a plurality of abrasive sleeves carried by and projecting in unbacked loop form peripherally beyond said drum for yieldably buffering work, core means within each of said sleeves for controlling the shape thereof, means associated with said core means for anchoring said sleeves to said drum, back-up means displaceable relative to said drum for presenting said work to said abrasive sleeves, means displaceable with said back-up means for yieldably resisting movement of said work past said buffering member independently of buffering pressure exerted thereon by said sleeves, and means carried by said back-up means for spreading said work prior to presentation thereof to said buffering member.

40 8. A buffer comprising a rotary drum, a plurality of abrasive sleeves carried by and projecting in unbacked loop form peripherally beyond said drum for yieldably buffering work, core means within each of said sleeves for controlling the shape thereof, means associated with said core means for anchoring said sleeves to said drum, back-up means shiftable relative to said drum for presenting said work to said abrasive sleeves, means for yieldably resisting movement of said work past said buffering member, and means for setting-out said work, said resisting and setting-out means being displaceable relative to said drum and operative on movement of said back-up means into buffering position relative to said sleeves.

45 9. A skin buffer comprising a rotary drum, a plurality of unbacked abrasive loops anchored to and projecting peripherally of said drum for yieldably buffering a skin, a back-up member associated with said drum and having a pair of jaws movable relative to each other and to said drum, one of said jaws carrying back-up means for presenting said skin to said loops, and means on 50 said jaws and cooperating on movement of said

11

one jaw to skin-presenting position for setting-out said skin and yieldably resisting movement thereof past said drum.

10. A skin buffer comprising a rotary drum, a plurality of unbacked abrasive loops anchored to and projecting peripherally of said drum for yieldably buffing a skin, a back-up member having a pair of relatively movable jaws, a back-up element on one of said jaws and normally removed from said loops for presenting a skin to said loops on movement of said jaw to operative position, gripping means carried by each of said jaws for yieldably resisting movement of said skin past said drum, and a plurality of angularly disposed sets of obliquely arranged rolls on each of said jaws for setting-out said skin, said gripping means and setting-out rolls being normally inoperative and coacting on movement of said one jaw to operative position.

11. A skin buffer comprising a rotary drum, a plurality of unbacked abrasive loops anchored to and projecting peripherally of said drum for yieldably buffing a skin, a back-up member having a pair of relatively movable jaws, one of said jaws having a back-up element and being oscillatable relative to said drum for moving said back-up element into skin-presenting position relative to said loops, gripping means carried by each of said jaws for yieldably resisting movement of said skin past said drum, and a plurality of angularly disposed sets of obliquely arranged rolls on each of said jaws for setting-out said skin, said gripping means and setting-out rolls being normally inoperative and coacting on movement of said one jaw to skin-presenting position.

12. In a skin buffer having a movable buffering device, a back-up member comprising a pair of normally open jaws for receiving a portion of a skin therebetween, back-up means carried by one of said jaws and operative on closing thereof for presenting a skin to said device, gripping elements carried by each of said jaws and cooperating to resist movement of said skin past said device, and a plurality of opposed outwardly facing sets of rolls arranged in echelon on each of said jaws and cooperating to set-out said skin, said gripping elements and setting-out rolls being normally inoperative and cooperating on closing of said jaws.

13. A buffering device comprising a movable support, a plurality of abrasive sleeves carried by and projecting in unbacked loop form beyond said support, a resilient core in each sleeve, said core normally expanding and inhibiting movement of said sleeve and being compressible to permit movement of said sleeve relative thereto, and clamping means engageable with said cores for releasably anchoring said sleeves therethrough to said support.

14. A buffering device comprising a movable support, a plurality of spaced seats on said support, abrasive sleeves seated in said seats and projecting beyond said support, a resilient core in each of said sleeves, said cores terminating outwardly intermediate outer extremities of said seats and sleeves, means on said cores for yieldably limiting the minimum projection of said sleeves, and clamping means engageable with said cores for releasably anchoring said sleeves therethrough in said seats.

15. A buffering roll comprising a rotary drum formed of a plurality of uniform sections, said drum having a plurality of circumferentially spaced, outwardly facing seats in the periphery

75

12

thereof, abrasive sleeves seated in said seats and projecting in loop form therebeyond, cores in said sleeves, said cores projecting above said seats and being spaced inwardly from said sleeves adjacent outer extremities thereof, and clamping means for releasably anchoring said cores and therethrough said sleeves in said seats.

16. A buffering roll comprising a rotary drum, said drum having a plurality of circumferentially spaced, axially extending, cylindrically concave seats interrupting the periphery thereof, a plurality of abrasive sleeves seatable in said seats, resilient tubular cores in said sleeves and adapted to conform to the contour of said seats, said cores each having reentrant wings projecting inwardly from either side thereof and connected therebetween and outturned legs beyond and below said wings and cooperating with said drum for fixing the position of said wings, said wings being spaced inwardly from said sleeves outwardly of said seats for limiting the minimum projection of said sleeves, and clamping means for anchoring said sleeves to said drum through said cores.

17. A buffering device comprising a movable support, abrasive loops carried by and projecting outwardly beyond said support, cores in and spaced inwardly of outermost portions of said loops for limiting the minimum projection of said loops, and clamps for anchoring said loops to said support through said cores.

18. A buffering device comprising a movable support, abrasive loops carried by and projecting outwardly beyond said support, cores in and spaced inwardly of outermost portions of said loops for controlling the shape and limiting the minimum projection of said loops, and clamping means engageable with said cores for anchoring said loops therethrough to said support.

19. A buffering device comprising a rotary support formed of a plurality of axially separable segments, circumferentially spaced seats in and interrupting peripheries of said segments, abrasive sleeves seatable in said seats, a core in and disposed inwardly of an outer extremity of each of said sleeves, and clamping means for anchoring said sleeves in said seats through said cores.

20. A buffering device comprising a rotary support formed of a plurality of axially separable segments, circumferentially spaced seats in and interrupting peripheries of said segments, abrasive sleeves seatable in said seats, a core in and disposed inwardly of an outer extremity of each of said sleeves, and clamping means common to certain of said sleeves for clamping said sleeves in said seats through said cores.

21. A buffering device comprising a rotary support formed of a plurality of axially separable segments, circumferentially spaced seats in and interrupting peripheries of said segments, seats of adjacent of said segments being staggered, abrasive sleeves seatable in said seats, a core in and disposed inwardly of an outer extremity of each of said sleeves, and clamping means for anchoring said sleeves in said seats through said cores.
